UNITED STATES PATENT OFFICE.

WARREN B. BUCKLEY, OF NEW YORK, N. Y.

DESIGN FOR A VEHICLE-TIRE.

50,121.

Specification for Design.

Patented Jan. 2, 1917.

Application filed October 14, 1916. Serial No. 125,744. Term of patent 14 years.

To all whom it may concern:

Be it known that I, WARREN B. BUCKLEY, a citizen of the United States, and residing at New York, in the county and State of New York, have invented a new, original, and ornamental Design for a Vehicle-Tire, of which the following is a specification, reference being had to the accompanying drawing, forming a part thereof.

Figure 1 is a plan view of a portion of a tire showing my new design. Fig. 2 is a cross sectional view on the line 2—2 in Fig. 1.

I claim:

The ornamental design for a vehicle tire, as shown.

WARREN B. BUCKLEY.
